UNITED STATES PATENT OFFICE.

RICHARD R. KINNEY, OF COLDWATER, MICHIGAN, ASSIGNOR TO THE NATIONAL BURIAL DEVICE COMPANY, OF COLDWATER, MICHIGAN.

BURIAL DEVICE.

SPECIFICATION forming part of Letters Patent No. 700,948, dated May 27, 1902.

Application filed October 28, 1899. Serial No. 735,058. (No model.)

To all whom it may concern:

Be it known that I, RICHARD R. KINNEY, a citizen of the United States, residing at the city of Coldwater, in the county of Branch and State of Michigan, have invented certain new and useful Improvements in Burial Devices, of which the following is a specification.

This invention relates to improvements in automatic releasing devices for burial apparatus, and is designed particularly for use in connection with that class of burial apparatus described in the patent to myself, granted on the 8th day of August, 1899, No. 630,459, and to myself and Gardner P. Barnard, which patent was issued on the 5th day of July, 1898, No. 606,722, although it is adapted for use in various other relations.

The objects of the invention are, first, to provide an automatic releasing device which shall be certain in its action and not liable to become accidentally detached; second, to provide such a device simple in its structure and operation.

Further objects will definitely appear in the detailed description to follow.

I accomplish these objects of my invention by the devices and means described in this specification.

The invention is clearly defined, and pointed out in the claims.

The structure embodying my invention is fully illustrated in the accompanying drawings, forming a part of this specification, in which—

Figure 1 is an enlarged detail view of my automatic detaching device. Fig. 2 is a detail sectional elevation, taken through my automatic detaching device when in use in relation to the box or casket, taken on a line corresponding to line 1-1 of Fig. 1. Fig. 3 is an enlarged detail perspective view of my automatic detaching device, showing the same as it appears after it has become automatically detached.

In the drawings the sectional view is taken looking in the direction of the little arrows at the ends of the section-lines, and similar letters of reference refer to similar parts throughout the several views.

Referring to the lettered parts of the draw-

ings, A B are a pair of oppositely-facing hooks. D D are lowering bands or cords, which connect these hooks to the lowering apparatus. E is the box or casket to be lowered. The engaging portions of the hooks engage with each other at slight angles to the perpendicular to make the engagement secure, portions being bended up for the entire width of the hooks, as A' and B', for this purpose. The hook is protected on its under side and opposite the engaging portion thereof with a shield B'', the shield and hook being formed from a continuous piece of sheet metal folded into the form indicated and having the hook formed on the upper side, hooking downward and inward, and the lower portion curved to form the shield B''. These parts are retained in position by rivets i, on which are placed suitable sleeves between the upper and lower portion on this hook. Links C, which move freely in each of the hooks A B, are secured thereto, and to these links are secured the webbing-bands, cords, or other means for lowering the coffin into a grave. The operation of this portion of the device is such that when supported in the position shown in Fig. 1 the ends of the lowering-tapes are joined very securely together, it being impossible to disengage the same by merely applying pressure thereto. When the coffin or casket is lowered into the grave and comes to rest upon the cross-pieces in the bottom of the coffin-box below, so that the pressure is relieved upon the lowering-bands, then the hooks drop apart automatically. The portion B'' of the hook B rests against the bottom of the coffin-box, and as soon as the pressure is slackened the rear portion drops downward, throwing the hook B upward, permitting the hook A to drop down onto the shield B'', and so disengaging, when the bands can be immediately withdrawn. Where no coffin-box is used, the shield portion B'' serves the same purpose of supporting the hook B in an elevated position and also prevents the hook A being accidentally supported in the engaging position by any obstacles in the bottom of the grave.

I have shown my invention in the form I believe to be most practical. I desire to state,

however, that it is capable of considerable variation in the details of construction without departing from my invention.

Having thus described my invention, what I claim as new, and desire to secure by Letters Patent, is—

1. In a burial device, the combination of the lowering belts or bands; a broad hook A made of sheet metal with a turned-up engaging portion A'; a broad hook B of sheet metal with a downwardly-turned engaging portion B', the metal being folded to form a shield B'' below the engaging-point of the hook B, a greater distance than the length of the engaging portion A' of the hook A, coacting as specified.
2. In a burial apparatus, the combination with lowering straps or cords; of a hook having an upwardly-projecting engaging portion on one of said straps or cords; and a hook on the opposite cord having a downwardly-pro-

jecting portion to support its point in an elevated position to permit the disengagement of the first hook when the tension is slackened.

3. In a burial apparatus, the combination of the lowering straps or cords; of a member having a downwardly-pointing hook portion; an opposite member having a hook adapted to engage said hook portion; and a support to hold the hook portion of said first member in an elevated position when the same is resting on the ground or floor, whereby said hooks will be disengaged when tension is slackened on the straps, for the purpose specified. 35

In witness whereof I have hereunto set my hand and seal in the presence of two witnesses.
